[57] CLAIM

The ornamental design for a syringe jacket with plunger handle, as shown and described.

DESCRIPTION

FIG. 1 is a perspective view of a syringe jacket with plunger handle, showing our new design;

FIG. 2 is a front elevational view thereof, the rear elevational view being identical thereto;

FIG. 3 is a bottom plan view of the handle portion, taken in the direction of line 3—3 of FIG. 2;

FIG. 4 is a top plan view of the syringe jacket portion, taken in the direction of line 4—4 of FIG. 2;

FIG. 5 is a side elevational view of the syringe jacket with handle, the opposite side elevational view being identical;

FIG. 6 is a top plan view thereof;

FIG. 7 is a bottom plan view thereof; and

FIG. 8 is an enlarged, fragmentary cross-sectional view taken along line 8—8 of FIG. 5.
